(57) **CLAIM**

The ornamental design for a contoured grip for writing instrument, as shown and described.

DESCRIPTION

FIG. 1 is a perspective view of a contoured grip of the present invention showing my new design;

FIG. 2 is a right side elevational view of the contoured grip of FIG. 1, the left side elevational view being a mirror image thereof, and the top and bottom plan views being the same; and,

FIG. 3 is a front elevational view of the contoured grip of FIG. 1.

Broken lines appearing in the Figures are for illustrative purposes only. They are intended to disclose the environment related to the claimed design and to define the bounds of the claim, but are not intended to be part of the claimed design. The rear elevational view forms no part of the claim design.
